PACKAGE NUMBERING OR LETTERING
MACHINE

William N. Freed, Richlandtown, Pa.

Application October 31, 1938, Serial No. 238,021

6 Claims. (Cl. 101—44)

This invention relates to package numbering or lettering machines and has for an object to provide a machine which will automatically remove a package from an endless conveyor, print the number or letter in any desired position or location on the package and return the package to the conveyor at greater speed than hitherto possible in similar devices.

A further object is to provide a machine of this character which will operate upon packages or containers regardless of shape or size, which can be adapted to any conveyor channel regardless of height, speed, width or length of the conveyor, or type of the conveying medium such as a chain, rubber belt, metal band, or wire mesh belt line.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a side elevation of a package numbering or lettering machine constructed in accordance with the invention with portions broken away.

Figure 2 is a plan view of the machine shown in Figure 1 with portions broken away.

Figure 3 is a detail cross sectional view taken on the line 3—3 of Figure 1.

Figure 4 is a cross sectional view taken on the line 4—4 of Figure 1 showing the star wheel, and printing mechanism in plan.

Figure 5 is a detail cross sectional view taken on the line 5—5 of Figure 4 showing one of the cam operated package clamping jaws.

Figure 6 is a detail cross sectional view taken on the line 6—6 of Figure 4.

Figure 7 is a vertical sectional view taken on the line 1—1 of Figure 2 showing the star wheel and adjacent parts.

Figure 8 is a detail cross sectional view taken on the line 8—8 of Figure 7 showing the slip clutch.

Figure 9 is a detail cross sectional view taken on the line 9—9 of Figure 7 showing the brake.

Figure 10 is a detail cross sectional view taken on the line 10—10 of Figure 4 showing the printing tape spools and feeding mechanism.

Figure 11 is a cross sectional view taken on the line 11—11 of Figure 10.

Figure 12 is a cross sectional view taken on the line 12—12 of Figure 11 showing the ratchet feed and reversing mechanism for the printing tape.

Figure 13 is a detail cross sectional view taken on the line 13—13 of Figure 10.

Figure 14 is a detail cross sectional view taken on the line 14—14 of Figure 12.

Figure 15 is a cross sectional view taken on the line 15—15 of Figure 11 and showing the printing wheels in front elevation.

Figure 16 is a cross sectional view taken on the line 16—16 of Figure 15.

Figure 17 is a cross sectional view taken on the line 17—17 of Figure 16.

Figure 18 is a detail cross sectional view taken on the line 18—18 of Figure 17.

Figure 19 is a cross sectional view taken on the line 19—19 of Figure 1 showing the cam and lever for actuating the printing mechanism.

Referring now to the drawings in which like characters of reference designate similar parts in the various views, 10 designates a conveyor of any conventional type adapted to transport packages such as labeled bottles, cartons, filled paper bags, cans, ampoules, tubes, and other containers.

The machine comprising the present invention is disposed laterally of the conveyor and is adapted to stamp a letter or number on containers momentarily removed automatically from the conveyor for this purpose.

In carrying out the invention the machine comprises a pedestal including a base 11 having a tubular upper portion loosely receiving a cylindrical standard 12 which is provided at the lower end with screw threads 13. A nut 14 is threadedly engaged with the threaded portion of the standard and bears upon the upper end of the base. By manipulating the nut the standard may be raised or lowered. A bottom frame plate 15 is secured to the upper end of the base in any suitable manner, preferably by screws 16 and extends toward the conveyor. A top plate 17 is secured to the standard preferably by screws 18 and overhangs the conveyor. The top and bottom plates form the frame of the apparatus for supporting the various parts.

Driving mechanism

By referring to Figures 1 and 2 it will be seen that the upper end of the standard 12 projects above the top frame plate 17 and is uniformly reduced to provide a shaft 19 upon which a gear 20 is loosely mounted. The gear meshes with, and is driven by a pinion 21 which is keyed to a stub shaft 22 disposed parallel to the shaft 19 and journaled at the upper end in a bearing arm 23 which is secured to the shaft 19. The stub shaft has keyed thereto, and is driven by, a worm gear 24 which meshes with a worm pinion 25 keyed to a shaft 26 which is journaled in bearings 27 on the upper frame plate 17 and which may be connected to any suitable source of power.

The gear 20 is provided with a hub 28 having an eccentric 29 integral therewith, and below the eccentric having a cam 30 integral therewith.

An eccentric strap 31, best shown in Figure 2, encircles the eccentric. A lever 32 is pivoted at one end on a pivot pin 33 which rises from the top plate and intermediate its ends is pivoted on a pivot pin 34 which rises from the eccentric strap. Thus when the gear 20 is rotated the eccentric rocks the lever 32, which will be hereinafter referred to as a rock lever, on the pivot pin 33. The purpose of this is to impart step actuation to the package holder about to be described.

Package holding star wheel and operating mechanism therefor.

As best shown in Figure 7 the package holder comprises superposed circular plates 35 and 36 having respective hubs 37 and 38 connected together by a pin 39. These plates form a package holder in the nature of a star wheel having four recesses, a quadrant apart, to successively receive packages 40 from the conveyor and present the same on the bottom frame plate 15 in position to be stamped as will presently be explained. One wall of each recess is provided with a pad 41 of yielding material against which the package, whether it be a bottle, can, or any other type or size of package, is clamped through the medium of a respective jaw 42 likewise faced with a pad 43 of yielding material as best shown in Figure 4.

The star wheel is secured to a stand shaft 44 through the medium of a slip clutch comprising a ball 45, as shown in Figure 7, which engages in a longitudinal groove 46 at the bottom of the shaft and is spring pressed through the medium of a helical spring 47 seated in an opening 48 formed in the hub 37 in the upper star wheel plate 35 and confined therein through the medium of a plug screw 49. Should any package 40 stick and tend to become broken, or to stop operation of the star wheel, the ball 45 will be forced out of the groove 46 and the star wheel thus will remain stationary while the shaft 44 continues uninterrupted axial rotation. The shaft 44 is journaled at the bottom in a bearing 50 formed on the end of a bracket arm 51 which is secured to the bottom fixed frame plate 15 through the medium of screws 52 or other connectors. A set screw 53 is engaged through one side of the bearing and has a reduced end which engages in a circumferential groove 54 formed in the shaft to prevent endwise displacement of the shaft from the bearing.

For imparting step rotation to the stand shaft 44 and star wheel carried thereby a ratchet wheel 55, best shown in Figure 2, is provided with a hub 56 which is keyed to the shaft 44 as shown at 57 in Figure 7. A rock lever 58 is provided with a hub 59 which is loose on the hub of the ratchet wheel and is retained thereon through the medium of a collar 60. One end of the lever is connected to the beforementioned rock lever 32 of the driving mechanism by a link 61, best shown in Figure 1. A pawl 62 is pivotally connected to the other end of the lever 58 and is held against the periphery of the ratchet wheel 55 through the medium of a helical spring 63.

The ratchet wheel is provided with four teeth 64 spaced a quadrant apart and in vertical alignment with the central planes of the package receiving recesses in the star wheel as best shown in Figure 2. When the eccentric strap 31 swings the rock lever 42 in one direction the lever 58 will be moved to carry the pawl 62 in a retrograde direction and lodge it in rear of a tooth 64. When

the eccentric moves the rock lever 32 in the opposite direction the lever 58 will be moved to carry the pawl 62, and with it the ratchet wheel 55, a step advance, that is through an arc of 90 degrees, the star wheel simultaneously, during such advance, removing a package 40 from the conveyor 10 and disposing it upon the bottom frame plate 15 in position to be stamped as will later be described. During the next step advance of the ratchet wheel 55 the star wheel 10 will be actuated to return the stamped package to the conveyor.

For preventing accidental movement of the ratchet wheel 55, a brake shoe 65, best shown in Figure 7, is mounted on the end of a screw 66 which is threadedly engaged in a lug 67 which rises from the end of the top movable frame plate 17.

The screw may be advanced to apply the shoe with sufficient friction to hold the ratchet wheel stationary when it is not being moved by the pawl 62. The screw is locked in this position through the medium of a lock nut 68.

The above mentioned link 61 is formed in two parts connected by a turnbuckle 69, best shown in Figure 2, which permits of the length of the shaft being varied to facilitate timing.

The hitherto mentioned jaws for clamping the packages 40 in place on the star wheel are best shown in Figure 4. The jaws are mounted on the upper plate 35 of the star wheel and are each carried by a respective lever 70 which is pivoted intermediate its ends on a pivot pin 71 and is provided at the free end with a roller 72 which rides upon the edge of a stationary cam 73. The lever is formed in two pieces at the roller end, one of which is provided with a longitudinal slot 74 through which an adjusting screw 75, carried by the other, is passed to vary the timing.

The stationary cam 73 is integral with the lower end of a sleeve 76 which loosely receives the stand shaft 44 and which is fixed at the upper end to a sleeve 77 through the medium of a screw 78. The sleeve 77 in turn is fixed to a boss 79 which depends from the bottom face of the upper movable frame plate 17 and to a bearing bushing 80 which extends through the plate, through the medium of a screw 81.

The roller of a respective lever 70 rides on to the high side of the cam 73 just as the container 40 is received in respective recesses of the upper and lower star wheel plates 35 and 36 and moves the respective jaw 42 to clamp the container in the star wheel and hold the same so clamped until the stamping operation is performed and the roller rides off of the high side of the cam on to the low side whereupon a controlling spring 82, connected to the lever and to the top plate 35 pulls the jaw back and releases the container which then gravitates onto the conveyor.

Stamping device and operating mechanism therefor

The stamping mechanism is shown in detail in Figures 12 to 18 inclusive. In the present embodiment of the invention a plurality of type wheels 83 are mounted upon a shaft 84 which is journaled at the ends in openings in a casing 85 which is open at the front to expose the type 70 86 on the wheels. While numerals have been illustrated, for the purpose of printing a serial number on a package or container, letters or other characters may be used. The casing 85 is mounted for lateral adjustment in an open front 75

casing 87, as best shown in Figure 18, through the medium of an adjusting screw 88 passed through a transverse slot 89 in the casing 87 and threadedly engaged with the casing 85.

5 The type wheels 83 increase in diameter from the centermost type wheel to the end type wheels, as best shown in Figure 16, and have their peripheries beveled to conform to an arc of a circle so that any selected number of the type wheels may 10 be used to accommodate the wheels to the contour of any package. The type wheels are provided with openings 90, best shown in Figure 17, concentric with the shaft 84, through which openings a pin 91 may be passed, as shown in Figure 16, 15 to lock the wheels in set position for displaying a selected serial number. The outer end of the pin is turned downward along the outer face of the casing 87, as shown at 92 in Figure 15, and this downturned end is engaged underneath a 20 leaf spring 93 carried by the casing to prevent endwise dislodgement of the pin through vibration or for any other cause.

The outer casing 87 is provided on the rear wall with a stem 94, best shown in Figures 11 and 25 17, which is received in a bore in the outer end of a shaft indicated in general by the numeral 95. A screw 96 having a smooth shank 97, is threaded into the shaft 95 and the shank is engaged through a slot 98 in the stem 94. A helical 30 spring 99 is disposed in the counterbore in rear of the stem. The shank 97 of the screw prevents rotation of the printing unit axially on the shaft while the spring 99 takes up the shock of impact when the printing unit impinges against the package 35 with the inked ribbon in front of the type, as will presently be explained. The slot 98 permits the printing unit to yield longitudinally of the shaft 95 against the tension of the spring 99.

The operating shaft 95 of the printing unit is 40 mounted, to reciprocate in bearings 100, best shown in Figures 4 and 11, formed on the upper end of vertically disposed posts 101 which are slidably fitted in openings 102 in the fixed bottom plate 15, as best shown in Figure 1. The lower 45 ends of the posts are connected by a cross bar 103 having a threaded nut 104 centrally disposed between its ends to receive the lower end of a feed screw 105 having a hand wheel 106 keyed thereto as shown at 107 in Figure 11. The hand wheel 50 may be manipulated to raise or lower the posts 101 for adjusting the height of the printing unit to operate on packages of various heights. The feed screw is rotatably mounted at the upper end in a bearing 108 which depends from the fixed 55 bottom plate 15. A screw 109 is threaded through the bearing and has a reduced end engaged in a circumferential slot 110 in the feed screw to mount the feed screw in the bearing.

The shaft 95 is formed in two sections connected by a turnbuckle 111 which permits of lengthwise adjustment of the shaft. At the end opposite the printing unit the shaft is equipped with rack teeth 112, best shown in Figure 4, which mesh with a pinion 113, of considerable length, 65 which is splined on a stand shaft 114 which extends parallel with the standard 12 and is rotatably mounted in the frame plates 15 and 17 of the machine.

When the shaft 14 is mechanically turned in 70 one direction as will be explained, the pinion 113 will move the shaft 95 outwardly to impress the serial number on the package. The shaft is immediately returned after the stamping operation through the medium of a helical spring 115 which is sleeved on the shaft 95 between a collar 75

116 thereon and the adjacent bearing 100, as best shown in Figure 4.

The pinion 113 is secured to the shaft 114 through the medium of a spline 117 which engages in a slot 118 formed longitudinally of the 5 shaft 114, to permit the pinion being raised and lowered on the shaft to accommodate various adjusted raised and lowered positions of the shaft 95 when the printing unit is adjusted to operate on different heights of packages. The pinion is 10 provided with a collar 119 through which a set screw 120 is passed as best shown in Figure 1, to secure the pinion in adjusted positions on the shaft 114.

Above the top frame plate 17 the shaft 114 is 15 provided with an arcuate crank arm 121, best shown in Figures 1, 2, 3 and 19. The crank arm is equipped at the free end with a roller 122 which rides upon a cam 123 which is integral with the hub 28 of the gear 29 below the eccentric 20 29. The crank arm 121 is arcuate in contour so that the cam 123 will only bear upon the roller 122 and not strike the crank arm. The high side of the cam is so positioned as to time the actuation of the printing unit operating shaft 95 to 25 alternate with the step advance movements of the star wheel. Thus after the star wheel has made a step advance to remove a package from the conveyor 10 and place it upon the bottom plate 15 of the machine in position to be stamped, 30 the cam 123 will rock the crank arm 121 to actuate the shaft 114 and shaft 95 and stamp the serial number on the package. This operation is only momentary, the stamping unit immediately being withdrawn by the before mentioned spring 35 115 the instant the high side of the cam 123 recedes from the roller 122.

Inked ribbon, reversible spools, and feeding mechanism therefor

40 As best shown in Figures 4, 10, 11 and 12 a bracket arm 124 is secured to the underneath face of the bearing 100 which is disposed next adjacent to the star wheel, through the medium of screws 125. A spindle 126 rises from each end 45 of the bracket and rotatably supports a respective spool 127 to which is secured a respective end of an inked ribbon 128. The ribbon is trained over rollers 129 carried by the outer casing 87 of the stamping unit, best shown in Figure 16, 50 these rollers having guide collars 130 to dispose the ribbon in front of the printing wheels 83, parallel with the axis of the printing wheels, as best shown in Figure 15.

The ribbon is selectively fed from one spool 55 and wound up on the other spool and for this purpose each spindle 126 is equipped above its spool with a ratchet wheel 131. The ratchet wheel is provided with a key 132 which enters one of a pair of longitudinal grooves 133 in the spindle, 60 as best shown in Figure 12. The spool is equipped with a pair of keys 134 which enter the grooves, as shown in Figure 13, so that the spindle, the spool and the ratchet wheel rotate as a unit.

It will be seen by referring to Figures 10 and 65 12 that a pair of arms 135 are pivotally connected at their outer ends to the spindles 126 through the medium of pivot pins 136. The inner ends of the arms are pivotally connected together through the medium of a pivot pin 137 70 which is engaged through a slot 138 in the bearing 100, as best shown in Figure 11, and threaded into the stamping unit operating shaft 95.

Each arm 135 is equipped with a dog 139 which 75 is slidably mounted in a bore 140 of rectangular

lar cross section, in the respective arm, as best shown in Figure 14. A spring 141 is disposed in the bore in rear of the dog, as best shown in Figure 10, to normally hold the dog engaged with the respective ratchet wheel 131. Normally only one of the dogs is in operative position, the other dog being withdrawn from engagement with its ratchet wheel and locked in release position through the medium of a screw 142, best shown in Figure 14, which projects from the dog and is equipped with a nut 143 which may be screwed up tight against the arm 135 to hold the dog disengaged.

As best shown in Figure 12 when the shaft 95 is reciprocated it carries the arms 135 forwardly with it to the dotted line position to move the operating dog in back of one of the teeth of its ratchet wheel 131, then when the beforementioned spring 115 returns the shaft 95 to the full line position the dog will advance the ratchet wheel one tooth and rotate the ribbon take-up spool a step while simultaneously the released dog permits the respective spool to feed off the ribbon.

In order to compensate for the increase of length of the arm 135 as it moves from a rectilinear position transversely of the shaft 19 to an inclined position, the arm is formed in two parts as best shown in Figure 10, the arm having an extension 144 which is engaged with the pin 137 and slidably fits in a counterbore 145 in the arm. A helical spring 146 is seated in the counterbore in rear of the extension to absorb shocks as the extension slides back and forth in the counterbore.

35

Operation

The package, bottle, can or other container proceeds on the conveyor belt into a cut-out in the star wheel and as the package enters the cut-out the moveable jaw 42 is closed to clamp the container by the rise of the roller 72 on the high side of the stationary cam 73 during rotary movement of the star wheel. The container gripped between the pads 41 and pad 42 of the jaw is carried by the rotating star wheel through a 90 degree angular advance into position on the fixed frame plate 36 in front of the stamping unit. The stamping operation is now performed, the stamp unit being moved forwardly by the shaft 38 which is actuated by the cam 123 on the gear hub 28 impinging against the arcuate lever arm 121. After the stamping operation the star wheel again rotates 90 degrees, returning the container to the conveyor belt, as the jaw 42 is moved to released position by the roller 72 riding on to the low side of the cam 73. The roller remains on the low side of the cam through an angular advance of 180 degrees to hold the jaw in open position and at the end of this movement the above cycle of operations is repeated.

Should the package or container not enter the cut-out of the star wheel properly the slip clutch releases, that is, the ball 45 is moved out of the groove 46 in the shaft 44 against the tension of its controlling spring to disconnect the star wheel from the power and permit the star wheel to remain stationary while the shaft 44 continues rotation. This prevents any serious damage to the mechanism of the machine as well as to the package or container itself.

The stamping wheels 83 force the inked rib-

bon 128 against the package or container, the type impressing the ink on the package or container to apply serial number, letter or other character. Retrograde movement of the stamping unit operating shaft 95, under urge of the spring 115, moves the active dog 135 to advance the ratchet wheel 131 of the ribbon wind-up spool one step so that a fresh surface is presented to the package or container when the stamping unit is next moved into operative position.

By referring to Figures 1 and 2 it will be seen that a hand wheel 147 is fixed on one end of the power shaft 26. This hand wheel permits turning over of the machine while adjustments are being made.

From the above description it is thought that the construction and operation of the invention will be fully understood without further explanation.

What is claimed is:

1. Container branding apparatus comprising the combination of an upright pedestal, superposed frame plates projecting laterally from the pedestal, means adjustably mounting the upper frame plate relatively to the lower frame plate to accommodate the device to operate on various heights of containers, a step-actuated star wheel carried by the lower plate adapted to dispose a container on the lower plate, vertically adjustable stamping means carried by the lower plate adapted to impinge against the sides of the containers, means to vertically adjust said stamping means and means for reciprocating the stamping means alternately with each step-actuation of the star wheel, said means being constructed and arranged to permit adjustment of the stamping means.

2. The device of claim 1 wherein the star wheel is circumferentially adjustable and means are provided for circumferentially adjusting the same.

3. The device of claim 1 wherein the step-actuation of the star wheel includes means for circumferentially adjusting the star wheel.

4. Container branding apparatus comprising the combination of an upright pedestal, superposed frame plates projecting laterally from the pedestal, means adjustably mounting the upper frame plate relatively to the lower frame plate to accommodate the device to operate on various heights of containers, a step-actuated star wheel carried by the lower plate adapted to dispose a container on the lower plate, stamping means carried by the lower plate adapted to impinge against the sides of the containers, said stamping means being adjustable axially of and transversely to the axis of said star wheel, means to adjust said stamping means and means for reciprocating the stamping means alternately with each step-actuation of the star wheel, said means being constructed and arranged to permit adjustment of the stamping means axially of said star wheel.

5. The device of claim 4 wherein the star wheel is circumferentially adjustable and means are provided for circumferentially adjusting the star wheel.

6. The device of claim 4 wherein the step-actuation of the star wheel includes means for circumferentially adjusting the star wheel.

WILLIAM N. FREED.
